UNITED STATES PATENT OFFICE.

RICHARD W. HAMANN, OF ST. LOUIS, MISSOURI, ASSIGNOR TO EUGENE J. FEINER, OF ST. LOUIS, MISSOURI.

BLAST APPARATUS FOR DOWNDRAFT-FURNACES.

SPECIFICATION forming part of Letters Patent No. 718,453, dated January 13, 1903.

Application filed September 2, 1902. Serial No. 121,761. (No model.)

To all whom it may concern:

Be it known that I, RICHARD W. HAMANN, of the city of St. Louis, State of Missouri, have invented certain new and useful Improvements in Blast Apparatus for Downdraft-Furnaces, of which the following is a full, clear, and exact description, reference being had to the accompanying drawings, forming a part hereof.

10 My invention relates to a blast apparatus for downdraft-furnaces; and it consists of the novel construction, combination, and arrangement of parts hereinafter shown, described, and claimed.

15 Figure 1 is a vertical longitudinal section of a downdraft-boiler. Fig. 2 is a front elevation of the blast apparatus. Fig. 3 is a view showing the automatic cut-off. Fig. 4 is an elevation of the blast apparatus with parts 20 removed, showing the steam-turbine. Fig. 5 is a perspective view of a casting which I employ in carrying out my invention. Fig. 6 is a perspective view of a deflector which I employ in carrying out my invention.

25 My invention is in the nature of an improvement on Letters Patent granted to me December 3, 1901, No. 688,171, on smoke-consumers, and especially designed to be used in connection with a downdraft-furnace, and especially constructed for such use. The use 30 of this invention with a downdraft-furnace I find by experience adds considerably to the efficiency of such a furnace, and on account of the draft apparatus being located in the 35 usual door-opening of a downdraft-furnace the heat which has heretofore emanated from such opening has been eliminated without affecting but adding to the efficiency of such furnace.

40 My draft apparatus, which will be described in detail hereinafter, is located in the usual door-opening of the downdraft-furnace.

Referring to the drawings, 1 indicates the 45 usual furnace-door opening of a downdraft-furnace, and over or in this opening I locate or attach my improved draft apparatus.

2 indicates a casting which is provided with a flange 3 and a groove 4 and a steam-port 5, and located in said steam-port 5 is one end of 50 a steam-pipe 6. Located in said casting 2, at

a point directly beneath the location of the steam-inlet pipe 6, is a steam-outlet pipe 7.

8 indicates a plate or diaphragm, which is snugly fitted and located in the groove 4, thus creating, in connection with the casting 2, 55 a chamber 9. Located in said chamber 9 is a steam-turbine 10, provided with cups 11, against which the steam entering the port 5 comes in contact by rotating the same. The steam-turbine 10 is mounted on a shaft 12. 60 Located in the casting 2 is a bushing or housing 13, provided with a peripheral flange 14, such bushing or housing 13 being readily mounted in the casting 2, said shaft 12 being located in the bushing or housing. 65

Mounted on the housing or bushing 13 is a metal cup 15, and secured to said metal cup 15 is a fan 16. When the steam-turbine is rotated, the fan 16 is actuated, thereby producing a blast, which blast or inward 70 current of air passes in through the opening 17 and into the furnace through the opening in the deflector 18, which is provided with a rectangular opening 19. Said deflector 18 is located in the groove 4 of the casting 2 and 75 is provided with a right-angular wall 20 and an inwardly-inclined wall 21. This deflector answers two purposes. By its being applied to the casting 2 a uniform size of blast apparatus may be made to fit various sizes of 80 door-openings of downdraft-furnaces, and then, again, the inclined wall 21 of such deflector deflects the air generated by the blast upwardly, or, in other words, elevates the same, so as to keep it from coming in contact 85 with the cold.

In operation the steam is admitted to the steam-inlet pipe 6 in the steam-port 5 and impinges on passing from said port on the buckets 11 of the steam-turbine, thus rotating the same, and by the operation of the steam-turbine the fan 16 is rotated, thus creating a current of air which passes through the opening 17 and into the furnace through the opening 19 of the deflector 18. 90

While I have shown in the drawings and described in the specification my invention as applied to a downdraft-furnace, I desire to state and emphasize that my invention can be equally as well applied and used 95 100

to other boiler-furnaces, so as to create by such use a force draft.

Of course when I apply my invention to a straight-draft boiler-furnace it is applied and 5 secured to the ash-pit opening.

What I claim is—

A blast apparatus for a downdraft-furnace, consisting of a casting 2 provided with a groove 4 and flange 3, and steam-port 5; a 10 plate 8 secured in said groove 4, thereby forming a steam-chamber 9, a steam-turbine located in said chamber, an air-fan adapted to

be actuated by said steam-turbine, and a deflector 18 mounted in said groove 4, said deflector consisting of a right-angular wall 20, 15 and an upwardly-inclined wall, substantially as specified.

In testimony whereof I affix my signature in presence of two witnesses.

RICHARD W. HAMANN.
